Inventor:
Chas H. Bush.

UNITED STATES PATENT OFFICE.

CHARLES H. BUSH, OF FALL RIVER, MASSACHUSETTS.

IMPROVEMENT IN BRUSHES FOR BOILER-FLUES.

Specification forming part of Letters Patent No. 55,815, dated June 26, 1866.

To all whom it may concern:

Be it known that I, CHARLES H. BUSH, of Fall River, in the county of Bristol and State of Massachusetts, have invented a new and useful Improvement on a Flue-Brush for Clearing Soot and other Substances from the Flues of Steam-Boilers; and I do hereby declare that the following is a full and exact description thereof, reference being had to the accompanying drawing, and to the letters of reference marked thereon.

My invention consists in an expansive and contracting brush—a brush separated in the center and provided with springs, so that it will adjust itself to the variations of the diameters of the flues when reciprocated through them.

The drawing is a perspective view of my invention.

A A A are halves of the brushes. B B are shafts, to which A A, &c., are firmly secured; C C C, elliptic spring fastened to B B. E is an adjusting-screw playing loose in the upper shaft, B, by which the two halves of the brush may be adjusted to enter the flue. Z Z show the opening when the parts of the brush are separated.

Operation: The flue-brush being constructed

as herein described, with elliptic spring and adjusting-screw, as shown, and adjusted to enter a flue, its operation and novelty may be noted.

By reciprocating the brush through the flue the spring permits it to contract or expand where the diameter of the flue is contracted or expanded, and thereby causes the brush to follow the uneven surface of the flue and remove the obstructions from it.

I do not confine myself to any particular form or size of brush, or form of spring, or to the form set forth for adjusting the brush for entering a flue. It may be constructed in any practical form or size, and adjusted to enter a flue by any practical device. Neither do I claim any device previously invented or patented for clearing flues; but

What I do claim as my invention, and desire to secure by Letters Patent, is—

An expanding and contracting brush for clearing obstructions from the flues of steam-boilers, constructed and operating as herein set forth and described.

CHAS. H. BUSH.
